DISPLAY FOOD CARTON

Leo Cesareo, Walpole, Mass.

Filed June 15, 1960, Ser. No. 60,981

Term of patent 14 years

(Cl. D58—12)

FIG. 1

FIG. 3

FIG. 1 is a rear perspective view of a display food carton showing my new design;

FIG. 2 is a front perspective view thereof; and

FIG. 3 is a bottom perspective view thereof.

I claim:

The ornamental design for a display food carton, substantially as shown.
